UNITED STATES PATENT OFFICE.

HENRY F. DRENK, OF RIVERSIDE, NEW JERSEY.

APPARATUS FOR SEPARATING AND UNRAVELING YARNS OF KNITTED FABRICS.

Application filed March 7, 1923. Serial No. 623,419.

To all whom it may concern:

Be it known that I, HENRY F. DRENK, a citizen of the United States, residing at Riverside, in the county of Burlington and

5 State of New Jersey, have invented certain new and useful Improvements in an Apparatus for Separating and Unraveling Yarns of Knitted Fabrics, of which the following is a specification.

10 This invention relates to improvements in means for reclaiming the yarns of knitted fabrics.

The primary object of this invention is the provision of means for effectively separating and backwinding the different interknitted yarns of fabric.

15 A very important object of this invention is the provision of a device embodying the above characteristics particularly well 20 adapted for use by hosiery manufacturers for the reclaiming of the yarn of defective hosiery, the improved device including means to effectively control the splicing yarn thereof, so that the main yarn may be readily 25 separated and unravelled therefrom.

20 A further object of this invention is the provision of a relatively simple, practical and highly efficient apparatus, for quickly unravelling knitted fabrics and backwinding 30 the same for reuse.

25 A further object of this invention is the provision of a device of the above mentioned character including means to quickly and effectively place a splice yarn controlling 35 member upon a fabric article, such as hosiery, from which the main yarn is to be separated.

30 Further objects of the invention are the provision of various cooperating details 40 which may be used in connection with the method and principle of this invention, so that practically any type of defective fabric or hosiery may have the expensive yarn reclaimed therefrom so that the same may be 45 used again.

40 Other objects and advantages of this invention will be apparent during the course of the following detailed description.

45 In the accompanying drawings, forming a part of this specification, and wherein similar reference characters designate corresponding parts throughout the several views,

50 Figure 1 is a side elevation of the improved apparatus, showing the manner in which the details of the same cooperate in

separating the splicing yarn from the main 60 yarn of a piece of hose, so that the main yarn may be unravelled for reclamation purposes.

Figure 2 is a fragmentary enlarged perspective view, showing the means by which the splicing yarn or other yarn of a fabric article, such as a piece of hose, may be controlled and separated to facilitate the unravelling of the main or other type of yarn therefrom.

Figure 3 is a plan view of the main portion of this invention showing cooperating 70 details thereof.

Figure 4 is a perspective view showing the manner in which an operator may quickly and conveniently apply the splice yarn control member upon a piece of hosiery or other knitted fabric, so that the same 75 will operate to maintain the splicing yarn free of the main yarn during unravelling of the latter.

Figure 5 is a longitudinal cross sectional view, taken through the improved device, 80 showing the application of the parts thereof as used with a piece of defective hosiery.

Figure 6 is a fragmentary view of the manner in which this invention may be used for unravelling yarn from defective fabrics, 85 even though the splicing yarn therein is mutilated, as is sometimes the case.

Figure 7 is a fragmentary perspective view of a modified detail of this invention.

In the drawings, wherein for the purpose 90 of illustration is shown but the preferred embodiment of this invention, the letter A generally designates the improved mechanism to separate and unravel knitted yarns of fabrics for reclaiming purposes, which 95 may include the mechanism B for receiving and acting upon the defective fabrics, and the winding apparatus C, of any approved type; both of said mechanisms B and C preferably being supported upon the machine base D.

100 In the manufacture of knitted articles, such as hosiery, underwear, and the like, a considerable portion of the articles, upon examination, are found to be defective, incident to ineffective working of the machine upon which they are knitted. Especially is this so in hosiery mills. This defective hosiery or other fabric article, if the same is knitted from single yarn thread without 110 splicing, may be easily reclaimed by back-winding the same in the manner well known

to those skilled in the art to which this invention pertains. However, in silk hosiery, as now manufactured, a splice runs from the heel to the top of the stocking.

5 The yarn of which this splice is formed is knitted with the silk yarn forming the main portion of the stocking, and if the stocking proves defective the reclaiming of the main yarn from the hosiery is extremely difficult, incident to the knitting of the splicing yarn therein. It has been the practice of manufacturers of hosiery to sell defective hosiery as "waste", since the cost of reclaiming the silk yarn from this type of hosiery was heretofore prohibitive.

10 Referring to the improved mechanism, and in detail to the apparatus B, the same includes the cylindrical shaped fabric holder 10, which in the illustration is cylindrical in formation, although the same may be of any shape to conform to the article which the same is to receive. This cylindrical shaped holder 10 is preferably formed of sheet metal, although the same

15 may be of wood or any analogous material, and is provided with a slot or opening 11 extending longitudinally inward from the outer surface thereof. The cylinder 10 illustrated may be rolled from a single

20 sheet of material until the beaded edges 12 and 13 thereof are in spaced relation to provide the slot or opening 11 of the proper width, and connecting or reinforcing clips 15 may be soldered or otherwise attached

25 within the holder 10, at the upper and lower ends thereof, so that the beaded edges 12 and 13 defining the slot or opening 11 are held in proper spaced relation throughout the height of the holder 10.

30 The fabric article E, which in the present instance is a piece of silk hosiery, is slipped over the holder 10 from the top thereof, and the same is drawn taut in engagement with the outer surface of the holder 10, longitudinally thereof. The upper part or top of the hose E, which is ordinarily of cotton and not worth reclaiming, is stuck upwardly within the compartment 15^a of the holder 10, as at 16, in Figure 5 of the drawings.

35 The boot or silk part 17 of the hose to be reclaimed is drawn taut upon the holder 10, as is illustrated in Figures 1 and 4 of the drawings. The splice 18 of the article E is arranged in confronting relation along the slot or opening 11, the same being of just sufficient width to lie inwardly of the beaded edges 12 and 13 of the holder 10, substantially as is illustrated in the drawings.

40 The hosiery is placed upon the holder 10 wrong side out, and the float portions or loose cross strands or threads 20 of the splice 18 are therefore outermost. The splice provided in silk hosiery is ordinarily cotton yarn, and is knitted in with the silk

45 yarn, so that it can readily be understood

that it is at best difficult to backwind the silk yarn for reclaiming purposes, since the cotton splicing yarn becomes entangled therewith incident to the fact that there is no constant force acting upon the same tending to separate the main and splicing yarns.

50 The novel member 30 is provided as an important part of this invention, the primary purpose of which is that of controlling the splicing yarn during unraveling of the silk yarn from the boot portion 17. This novel member 30 preferably includes a relatively long rod 31, having the upper end 33 thereof flattened and provided with a hook shaped head or offset portion 34 arranged in a plane at an acute angle with respect to the portion 33. The extreme lower end of the cylindrical shaped rod 31 is rounded, as at 35, to facilitate sliding of the rod 31 between the splice threads or yarn, as will hereinafter be more fully set forth.

55 In operation, the knitted fabric article such as the hose E having been placed upon the holder 10, the holder 10 is disposed vertically upright upon the machine base or bed D. The operator next grasps the novel splice yarn controlling member 30, as is illustrated in Figure 4, and after inserting the rounded end 35 rearward of the topmost loose cross threads 20, and pushing inwardly toward the opening 11 and against the splice 18, the rod 31 may be readily slid downwardly intermediate the splice and the loose splice threads 20, substantially as is illustrated in Figure 4 of the drawings. This operation is facilitated incident to the provision of the beaded edges 12 and 13, and the opening 11, and may be effected without any trouble whatsoever. An aperture 40 is provided in the machine bed or base D through which the lower end of the rod portion 31 extends, so that the member 30 is free to descend by gravity as the silk yarn is unravelled or back wound from the holder 10. The hook portion 34 of the member 30, of course, rests upon the loose strands of the splice yarn, substantially as is illustrated in Figures 1, 2, and 5 of the drawings. The silk yarn from the boot portion 17 is loosened at the top by the operator, and a thread 43 thereof extended toward and about the conventional guide hook 44, and brought downwardly for winding about the vertical bobbin or spool 45. The mechanism C is of any approved type, and controls the silk yarn as the same is unravelled from the holder 10, and backwinds the same upon the bobbin 45.

60 As is illustrated in Figure 2 of the drawings, the silk yarn 43, as the same is loosened by means of the back winding mechanism C and unravelled from the hose E, will

free the yarn of the splice 18. As this yarn of the splice 18 is all connected, the member 30 acting by gravity upon the same will draw or exert a pull downward upon the 5 same, so that as said splice yarn is loosened, incident to unraveling of the silk yarn from the main portion of the hosiery or article E, the same will be effectively separated and segregated from the unravelled silk yarn 10 and there will be no liability of twisting or knotting of the splice and main yarns, as is very evident. As the silk yarn is unwound from the boot portion 17 of the article E, the splice yarn controlling member 30 will 15 drop, always exerting a pull upon the top-most thread of the splice yarn. After being in operation for a considerable time, the loosened splice yarn upon the head 34 may pass downwardly thereof and fall free 20 from the apparatus B, or the operator may, by his or her finger, remove the same from the upper end of the member 30. As is illustrated in Figure 6, a special type of splice yarn controlling member 50 is provided 25 which is adapted for use when the outer loose cross threads of the splice are mutilated or cut, as at 51. This member 50 provides a rod portion 52 of very small diameter, which can be threaded between 30 the main threads and inside splice threads, where the threads of the splice are just sufficient to permit the rod 52 to be inserted as hereinbefore described. Again, in the reclaiming of yarns from the foot portion 35 of the hosiery, a special type of member 55 will have to be provided, which includes a rod portion 56 of ordinary diameter, and a hook portion 57 providing a very broad inclined arm 58 corresponding to the arm portion 34 of the first mentioned splice yarn controlling member 30. It can readily be appreciated that the feet of hosiery cannot 40 be unravelled upon the same type of holder as is provided for the boot portion of the hosiery, since in the former case the slot in the holder will, of necessity, have to be very wide, to accommodate the wide double sole provided in practically all types of 45 silk hosiery. In this case, the special control member 55 is used as by the provision of the very broad head portion 57 thereon, the loosened cotton threads which it is desired to separate from the silk yarn will 50 not be pulled to an undue extent, and cannot 55 drop from the arm 58 or in any way get mixed with the silk yarn being unravelled.

From the foregoing description of this 60 invention, it is apparent that a practical apparatus has been provided, and an improved method has been devised, whereby the silk yarn from defective hosiery and other knitted articles may be reclaimed and separated from splice or other yarns interknitted therewith. When it is considered

that at present larger manufacturers of silk hosiery and fabric are selling defective hosiery, such as the type E in the illustration, at four cents a pound; the silk entering the same originally having cost the 70 manufacturer approximately eight dollars and seventy-five cents a pound, the fact that the silk yarn may be reclaimed by means of the improved apparatus B for approximately twenty to thirty cents a pound will 75 very materially reduce the loss in production from defective articles and a considerable economy resulting thereby both to the manufacturer and the public.

The apparatus by means of which the 80 method herein described and claimed is effected may be altered considerably to conform to the requirements of various articles to be reclaimed of valuable yarn therein.

Various changes in the shape, size and 85 arrangement of parts may be made to the form of invention herein shown and described, without departing from the spirit of the invention or the scope of the claims.

I claim:

1. An apparatus for separating and unraveling the main and splice yarns of hosiery comprising a hosiery holder, backwinding means for the main yarn of the hosiery, and a weight supported by the splice yarn 95 to exert a constant pull on the same during unraveling of the main yarn to separate it therefrom.

2. An apparatus for separating and unraveling the main and splice yarns of hosiery comprising a hosiery holder, backwinding means for the main yarn of the hosiery, weight means for controlling the splice yarn including a rod portion extending through the splice intermediate the yarn thereof and 100 the main yarn, and a head for engaging the splice yarn at the unraveling end of the hosiery.

3. As an article of manufacture, a fabric holder for yarn unraveling apparatus 110 formed of sheet metal having the longitudinal edges thereof beaded, said holder being rolled so that said edges are in spaced substantially parallel relation, and means connecting said edges in spaced relation to 115 provide a longitudinal opening inwardly of the side of the holder.

4. Apparatus for separating and unraveling main and splice yarns from hosiery, comprising a hosiery supporting member 120 having an opening inwardly of the outer surface thereof and extending longitudinally thereof to receive the splice of the hosiery in confronting relation therewith, a member adapted to be supported by hosiery 125 in said opening for engaging and pulling upon the splice yarn, and unraveling means for the main yarn.

5. Apparatus for separating and unraveling main and splice yarns from defective 130

hosiery, comprising a hosiery holder adapted to receive the hosiery thereon, and a gravity member threaded through the loose splice yarn longitudinally of the hosiery to act upon said splice yarn while the main yarn is being unravelled from said hosiery whereby the latter may be unravelled free of entangling with the splice yarn.

6. Apparatus for separating and unravelling main and splice yarns from hosiery comprising a holder for tautly receiving the hosiery, said holder having an opening inwardly of the side thereof extending longitudinally thereof along which the splice 10 yarn is adapted to be placed, and a rod member having a hooked end, said rod being adapted for threading through the splice yarn with the head thereof resting upon the uppermost cross strands of the 15 splice yarn, so that during unravelling of the main yarn from the hosiery said member will act by gravity to pull the splice 20 yarn free of the main yarn.

7. Apparatus for separating and unravelling main threads from splice threads of fabric where the splice threads have float portions comprising means to support the fabric, means for unravelling the main thread, and means acting on the float portions of 25 the splice thread to exert a force thereon tending to maintain the splice thread free from the raveling edge of the fabric as the splice thread is loosened incident to unravelling of the main thread.

30 8. Apparatus for separating and unravelling main and splice yarns of fabric garments where the splice yarns have float portions loosely outstanding from the main yarn comprising a holder for receiving the garment thereon providing a way therealong which the splice faces, and a weight member adapted to extend along said way between the main yarn and the float portions of the splice and acting by gravity 35 on the float portions of the splice yarn at the raveling edge of the garment whereby to draw the splice yarn free of the main yarn as the latter is unravelled.

40 9. Apparatus for unravelling and separating yarns comprising a holder adapted to receive the article to be unravelled, and an elongated member adapted to be supported

45 by the article in movable relation with respect to the holder to bear by gravity on a certain yarn in the article to permit unhampered unravelling of another yarn in the article substantially as described.

50 10. In apparatus for separating and unravelling the splice threads from the main yarn of hosiery the combination of a substantially cylindrically shaped support adapted to receive the hosiery in taut relation thereover and including a way longitudinally thereof with the splice threads faced so that float portions of the splice 55 threads face outwardly, and a splice thread controlling member including a rod portion threaded in the splice between the float portions of the spliced threads and the main 60 yarn and including a head resting by gravity on the uppermost splice thread float portions, whereby incident to unravelling of the main 65 yarn the splice threads will be drawn by said member away from the raveling edge of the hosiery.

70 11. Apparatus for separating and unravelling the main and splice yarns of a garment comprising means to receive the garment thereover including a way along which the splice yarn is disposed, and means acting 75 along said way on said splice yarn to pull the said splice yarn away from the raveling edge of the garment as the main 80 yarn is unravelled from the garment.

85 12. Apparatus for separating and unravelling main threads from splice threads of fabric where the splice threads have float portions, comprising means to support the fabric, means for unravelling the main thread, and a splice thread controlling member including a rod portion adapted to extend between the float portions of the splice 90 threads and the adjacent portions of the fabric and including a substantially hook-shaped head adapted to rest by gravity on the float portions of the splice thread adjacent the raveling edge, said hook-shaped 95 head being bent to provide an inclined end portion arranged substantially at an acute angle with respect to the length of the rod portion whereby to carry the splice thread 100 portions which are loosened away from the raveling edge of the fabric.

HENRY F. DRENK.
